SKIN FASTENER

Peter F. Rossmann, Snyder, N. Y., assignor to
Irving Rossi, West Orange, N. J.

Application December 19, 1941, Serial No. 423,565

7 Claims. (Cl. 85—5)

The present invention relates to a clamp or skin fastener for temporarily assembling or clamping together perforated sheet material, in particular metal sheets or plates preparatory to and to facilitate a riveting operation or other work to be carried out on said material.

In my co-pending application, Serial No. 384,461, filed March 21, 1941, entitled Clamping device, I have described a device of this character comprising essentially a body member or support having an opening preferably equal to the perforations in the sheets to be clamped, a clamping element movable relative to said support and having a pair of resilient legs or prongs provided with shoulders and biased towards each other, and a spreader arranged in fixed relation to said support and projecting through said opening. The spreader is interposed between said prongs to hold the same in spaced apart position against their natural bias with the combined cross-sectional area of said prongs and spreader being substantially equal to and filling said opening. Furthermore, suitable spring means are arranged interposed between said spreader and said clamping element to permit of movement of said clamping element between two extreme positions, one of said positions causing the ends of said prongs and said shoulders to pass beyond said spreader and to be operated into engagement with each other in such a manner as to enable the insertion of said prongs through the aligned perforations of the pair of sheets to be clamped, and the other of said positions causing clamping engagement and a firm locking of said sheets between said support and said shoulders held in spaced apart position by said spreader.

The object of the present invention is to provide a number of improved features in a device of the above general character is an effort to simplify the design and improve the operation thereof.

A specific object is to provide a simplified skin fastener the component parts of which are reduced to a minimum and can be easily assembled and disassembled for exchange of broken or defective components.

Another object is to permit of the use of a heavy clamping force substantially without damage to the metal sheet or other material being clamped or assembled.

A further object is the provision of a simplified clamping member constructed in such a manner as to enable quick and instant insertion through the perforations in the sheets to be clamped even

in the hands of an unskilled or untrained operator.

The above and further objects and advantages of the invention will become more apparent from the following detailed description taken with reference to the accompanying drawing forming part of this specification and wherein:

Figure 1 is a vertical cross-sectional view of a skin fastener constructed in accordance with the principles of the invention;

Figure 2 is a cross-sectional view taken on line 2—2 of Figure 1;

Figure 3 is a partial view of the improved and simplified clamping element;

Figure 4 is a perspective partial view showing the spreader member embodied in Figure 1;

Figure 5 is a vertical view showing the fastener in the inserting position during the operating cycle; and

Figure 6 is a perspective view showing the novel locking element for holding the parts of the device in assembled position.

Like reference characters identify like parts in the different views of the drawing.

In the drawing, the numeral 10 indicates the body member or support of my improved fastener having, in the example shown, the shape of a cup provided with a flange 10' at its open end and having a curved or outwardly vaulted bottom provided with a central opening therein which is preferably equal to the aligned perforations in the sheets A and B, or any other piece to be clamped or assembled. Item 11 represents the clamping element which is shown separately in Figure 3 and according to the improved construction is constituted by a unitary wire member of semi-circular or segmental cross-section (see Figure 2) bent in U-fashion with the flat surfaces facing each other to form a pair of legs or prongs. The latter are furthermore shaped in such a manner as to comprise a first pair of substantially parallel sections 12 and 12' adjacent to their bent end followed by intermediate sections 13 and 13' bent inwardly at a small angle (about 15°) to the central or symmetry line. Sections 13 and 13' are in turn followed by further sections 14 and 14' bent outwardly at a slight angle (about 3°), while the lowermost or outer sections 15 and 15' provided with shoulders or protuberances 16 and 16' are again substantially parallel and urged or biased towards each other in the normal position as shown in Figure 3.

The parallel outer sections 15 and 15' are passed through the opening in the bottom of the cup 10 and are held in spaced apart position both

55

in the ineffective or non-use and in the operative positions by a substantially T-shaped spreader (Figure 4) having a cross-piece 17 and a spreader member 18 interposed between and being in sliding engagement with the flat inner faces of the prong portions 15 and 15' as shown in Figure 1. The under-surface of the spreader portion 17 is suitably curved to conform to the inside of the bottom wall of the cup or body member 10. The clamping member 11 projects beyond the member 10 and has its upper bent end secured to a head or cap 20 by the aid of a cross-pin 21 passing through diametrical perforations in the cap and embracing the bent upper portion of the prongs. Pin 21 is held in position by a slit resilient annular-shaped locking element 23 placed in a circumferential groove of the cap to enable easy assembly and disassembly of the device during manufacture and for the quick exchange of broken or defective parts during use. A coil spring 22 surrounding the prongs of member 11 has its lower end engaging the spreader portion 17, the upper end of the spring resting within a recess in the under-surface of and engaging the cap 20. Spring 22 is designed to provide sufficient clamping force to firmly lock the shoulders 16 and 16' against the under-surface of sheet B in the operative position of the fastener as shown in Figure 1 or against the under-surface of the cup 10 in the non-use position of the device. The vaulted or curved construction of the bottom wall of the cup or body member 10 enables the employment of a heavy spring to secure an adequate clamping or firm locking of the sheets A and B with the fastener without the danger of damage to the sheets or other piece to be clamped or assembled.

While I have shown the support or body member 10 in the form of a cup it will be understood that the same may take any other suitable shape such as a U-shaped metal strip or angle piece or the like, such modifications and variations of the component parts of the device being readily obvious to those skilled in the art.

In use, the cap 20 is pressed towards the cup 10 by compressing the spring 22 preferably with the aid of a suitable tool such as a toggle device or a plier engaging the upper surface of the cap on the one hand and the under-surface of the flange 10' on the other hand. In this (inserting) position the prong sections 15 and 15' have passed beyond the spreader portion 18 and are operated into engagement with each other in such a manner as to allow of ready insertion of the prongs through the holes in the sheets A and B, as shown in Figure 5 which illustrates the position at the beginning of the insertion cycle. The shoulders 16 and 16' are designed in such a manner as to provide, when in engagement with each other, a slip fit in the perforations and, due to the parallel shape of the lower sections of the prongs 15 and 15', it is clearly seen that the insertion is greatly simplified by providing ready guidance of the prongs through the perforations during the inserting operation. In this position the spreader portion 18 which substantially conforms to the inner faces of the prong sections 14 and 14' will be readily positioned between the latter, resulting in the prongs remaining properly aligned and preventing lateral movement or canting as is readily understood.

At the end of the insertion cycle, that is after the vaulted bottom of the cup member 10 engages the upper surface of the sheet A (Figure 1), the spreader part 18 will project sufficiently be-

yond the lower sheet B to cause the sections 15 and 15' and the shoulders 16 and 16' to become spread apart by moving in an upward direction towards the body member upon release of the spring 22 so as to result in a firm locking or clamping of the sheets between the shoulders and the member 10.

In order to remove the fastener, the spring is again compressed by pressing the cap 20 against the cup 10 thereby operating the prong sections 15 and 15' into engagement with each other and enabling a withdrawal of the prongs from the perforations in a manner readily understood from the above.

15 It will be evident from the foregoing that the invention is not limited to the specific details of construction and arrangement of parts shown and disclosed herein for illustration, but that the underlying novel principles are susceptible of variations and modifications coming within the broader scope of the invention as defined in the appended claims. The specification and drawing are accordingly to be regarded in an illustrative rather than a limiting sense.

25 I claim:

1. In a clamp for clamping sheets through perforations therethrough, a body member having an outwardly vaulted bearing surface provided with a central opening and engaging said sheets, 30 a clamping element projecting through said opening and having a pair of prongs provided with shoulders and biased towards each other, a spreader in fixed relation to said body and interposed between said prongs, and means including 35 springs means interposed between said body and said element for causing clamping action between said shoulders and said body upon movement of said element towards said body and compression and subsequent release of said spring means.

40 2. In a clamp for clamping sheets through perforations therethrough, a body member having an outwardly vaulted bearing surface provided with a central opening and engaging said sheets, 45 a clamping element projecting through said opening, said clamping element being constituted by a unitary wire member bent in U-fashion to provide a pair of resilient prongs having shoulders and biased towards each other, a spreader in fixed relation to said body and interposed between 50 said prongs, and means including spring means interposed between said body and said element for causing clamping action between said shoulders and said body upon movement of said element towards said body by compression and subsequent release of said spring means.

55 3. In a clamp for clamping sheets through perforations therethrough, a body member having an outwardly vaulted bearing surface provided with a central opening substantially equal to the 60 aligned perforations in the sheets to be clamped, said bearing surface engaging said sheets in the clamping position, a clamping element projecting through said opening, said clamping element being constituted by a unitary wire member bent in U-fashion to provide a pair of resilient prongs having shoulders and biased towards each other, a spreader in fixed relation to said body and interposed between 65 said prongs, and means including spring means interposed between said body and said element for causing clamping action between said shoulders and said body upon movement of said element towards said body by compression and subsequent release of said spring means.

70 4. In a clamp for clamping sheets through per-

forations therethrough, a body member having an outwardly vaulted bearing surface provided with a central opening and engaging said sheets, a clamping element projecting through said opening having a pair of resilient prongs provided with shoulders at the ends thereof and biased towards each other, a spreader conforming to and resting against the inner surface of said body, said spreader having an extension interposed between said prongs, and means including spring means interposed between said spreader and said body for causing clamping action between said shoulders and said body upon movement of said element towards said body and compression and subsequent release of said spring means.

5. In a clamp for clamping sheets through perforations therethrough, a body member having an outwardly vaulted bearing surface provided with a central opening and engaging said sheets, a clamping element projecting through said opening having a pair of prongs provided with shoulders and biased towards each other, a spreader frictionally engaging said body and having a portion interposed between said prongs, and means including spring means interposed between said spreader and said clamping element for causing clamping action between said body and said shoulders held in spaced-apart position by said spreader portion.

6. In a clamp for clamping sheets through per-

forations therethrough, a body member having an outwardly vaulted bearing surface provided with a central opening and engaging said sheets, a clamping element projecting through said opening, said clamping element being constituted by a unitary wire member bent in U fashion to provide a pair of resilient prongs having shoulders and biased towards each other, a spreader frictionally engaging said body and having a portion interposed between said prongs, and means including spring means between said spreader and said element for causing clamping action between said body and said shoulders held in spaced-apart position by said spreader portion.

15 7. In a clamp for clamping sheets through perforations therethrough, a body member having an outwardly vaulted bearing surface provided with a central opening and engaging said sheets, a clamping element projecting through said opening and having a pair of prongs provided with shoulders at the ends thereof and biased towards each other, a spreader conforming to and frictionally engaging the inside of said bearing surface, said spreader having a transverse extension interposed between said prongs, and means including spring means interposed between said spreader and said element for causing clamping action between said body and said shoulders held in spaced-apart position by said extension.
